CLAIM

The ornamental design for an essential oil diffuser, as shown and described.

DESCRIPTION

FIG. 1 is a front elevational view of an essential oil diffuser showing my new design;

FIG. 2 is a rear elevational view thereof;

FIG. 3 is a right side view thereof;

FIG. 4 is a top plan view thereof;

FIG. 5 is a bottom plan view thereof; and,

FIG. 6 is a perspective view thereof.

FIG. 3 is a right side view thereof, the left side view being a mirror image of the right side view.

The broken lines shown form no part of the claimed design.
